Patented Apr. 4, 1922.

UNITED STATES PATENT OFFICE.

CHARLES A. GREENE, OF LOS ANGELES, CALIFORNIA.

CLAMP.

1,411,569.

Specification of Letters Patent.

Patented Apr. 4, 1922.

Application filed March 24, 1921. Serial No. 455,096.

To all whom it may concern:

Be it known that I, CHARLES A. GREENE, a citizen of the United States, residing at Los Angeles, in the county of Los Angeles 5 and State of California, have invented new and useful Improvements in Clamps, of which the following is a specification.

It is the object of this invention to provide a clamp which, while adapted for general use, is particularly useful for an invalid lifting device wherein a plurality of the clamps are provided upon a frame, so that the clamps may engage the corners of bed clothing upon which an invalid rests, 15 in order that the invalid may be raised by lifting the frame having the clamps connected thereto.

The clamp provides an extremely simple but efficient arrangement whereby bed clothing, or the like, may be positively held between the jaws of the clamp which are movable relative to one another with one of said jaws provided with connecting means whereby the clamp may be secured to a suitable 25 frame, such as the frame of an invalid lifting mechanism.

The invention will be readily understood from the following description of the accompanying drawings, in which—

30 Figure 1 is a perspective view showing the improved clamps employed in an invalid lifting device with the clamps engaging the bed clothing upon which the invalid rests.

Fig. 2 is a rear elevation of the clamp.

35 Figs. 3 and 4 are longitudinal sections on the line 3—3 of Fig. 2 and showing the clamp swung to closed clamping position and in open disengaging position respectively.

40 The improved clamps may be employed in connection with individual lifting mechanism which may comprise side bars 1 connected by a cross bar 2 so as to form a frame which may be lifted in any suitable manner.

45 The clamps are connected to the respective ends of side bars 1 and are adapted to engage the respective corners of bed clothes 3 upon which an invalid rests and in order that the invalid may be readily lifted.

50 Each of the clamps comprises a stirrup 4 having a clamping base 5 and a rod 6 pivoted to the upper end of the stirrup. An eye bolt 7 may be connected to the end of the rod, and said eye bolt is adapted to be received through one of the side bars 1 and

held in place by a nut 8 so that rod 6 and stirrup 4 depend from the side bar.

A second stirrup 9 is received over stirrup 4, and the stirrup 9 is pivoted to the stirrup 4 by pins 10 received through the 60 side bars of the respective stirrups. The upper ends of stirrup 9 are connected by a pin 11 against which rod 6 is adapted to abut in order to swing the stirrups into closed position relative to one another when pull is 65 exerted upon rod 6, as will be readily understood by reference to Figs 3 and 4. The base 12 of stirrup 9 is adapted to overlie the base 5 of the stirrup 4 when the stirrups are swung into alinement, as shown in Fig. 3, and the 70 bases 5—12 are preferably inclined, as clearly shown in Fig. 3, with the adjacent surfaces of said bases provided with projecting teeth 75 13 arranged in offset relation upon the respective bases, so as to move past one another as the stirrups are swung into alinement, in order to form means for clamping bed clothes 3 between said toothed surfaces.

It will be understood that when it is desired to engage bed clothes by the clamp 80 that the stirrups are swung into alinement, as shown in Fig. 3, so that the toothed surfaces 13 will engage the respective sides of the bed clothes and clamp the latter between the bases of the stirrups. In order to disengage the bed clothes, it is only necessary to swing stirrup 9 upon pivot pins 10, as shown in Fig. 4, so that the clamping bases 5—12 are swung out of alinement and into a position providing for the ready removal 90 of the bed clothes.

Various changes may be made without departing from the spirit of the invention as claimed.

What is claimed is:

1. A clamp comprising stirrups comprising U-shaped members pivoted one within the other and having bases adapted to be brought into alinement to form clamping engagement with a member between said 100 bases.

2. A clamp comprising stirrups comprising U-shaped members pivoted one within the other and having connecting means secured to one of said stirrups, said stirrups 105 also having bases adapted to be brought into alinement to form clamping engagement with a member between said bases.

3. A clamp comprising stirrups pivoted one within the other and having bases in- 110

clined with relation to the sides of said stirrups, and adapted to be brought into alinement to form clamping engagement with a member between said bases.

5. 4. A clamp comprising stirrups comprising U-shaped members pivoted one within the other and having co-operating toothed bases adapted to be brought into alinement to form clamping engagement with a member between said bases.

10. 5. A clamp comprising stirrups pivoted

one within the other and having connecting means secured to one of said stirrups, said stirrups also having bases inclined with relation to the sides of said stirrups and provided with co-operating teeth adapted to be brought into alinement to form clamping engagement with a member between said bases.

15. In testimony whereof I have signed my name to this specification.

CHARLES A. GREENE.
